US0D1039425S

(12) **United States Design Patent** (10) Patent No.: **US D1,039,425 S**
(45) Date of Patent: ** Aug. 20, 2024

(54) **DRONE**

(71) Applicant: **HANGZHOU ZERO ZERO TECHNOLOGY CO., LTD**, Hangzhou (CN)

(72) Inventors: **Jingming Liu**, Zhejiang (CN); **Long Zhang**, Zhejiang (CN); **Chenhui Qian**, Zhejiang (CN)

(73) Assignee: **HANGZHOU ZERO ZERO TECHNOLOGY CO., LTD**, Hangzhou (CN)

(**) Term: **15 Years**

(21) Appl. No.: **35/516,920**

(22) Filed: **Mar. 31, 2023**

(80) **Hague Agreement Data**

Int. Filing Date: **Mar. 31, 2023**

Int. Reg. No.: **DM/228098**

Int. Reg. Date: **Mar. 31, 2023**

Int. Reg. Pub. Date: **Apr. 21, 2023**

(30) **Foreign Application Priority Data**

Oct. 28, 2022 (CN) 202230717173.0
Oct. 28, 2022 (CN) 202230717222.0

(51) LOC (14) Cl. **12-01**

(52) U.S. Cl.

USPC **D12/16.1**

(58) **Field of Classification Search**

USPC D12/16.1, 174, 319-345; D21/436-455
CPC B64C 29/0033; B64C 2201/021; B64C 29/02; B64C 2201/088; B64C 2201/104; B64C 2201/141

See application file for complete search history.
